UNITED STATES PATENT OFFICE.

LEWIS MOORE, OF JOLIET, ILLINOIS.

DESIGN FOR A HEATING STOVE.

Application filed September 26, 1925. Serial No. 14,915. Term of patent 14 years.

To all whom it may concern:

Be it known that I, LEWIS MOORE, a citizen of the United States, residing at Joliet, in the county of Will and State of Illinois, have invented a new, original, and ornamental Design for Heating Stove, of which the following is a specification, reference being had to the accompanying drawings, forming a part thereof.

On the drawing:

Fig. 1 is a perspective view showing the front of a stove embodying my design;

Fig. 2 is a perspective view showing the rear side and top of the stove, and

Fig. 3 is a top plan view showing the top of the stove.

I claim:

The ornamental design for a heating stove, as shown.

LEWIS MOORE.
